MICROPHONE

Cecil K. Stedman, Watertown, and Frederick H. Smith, East Natick, Mass., assignors to the United States of America as represented by the Secretary of the Navy

Application September 11, 1943, Serial No. 502,076

1 Claim. (Cl. 340—8)

1

This invention relates to microphones and more particularly to a novel magnetostriuctive microphone of simple and compact construction which is sensitive and directionally selective in operation.

One object of the invention resides in the provision of a novel microphone of the magnetostriuctive type for use in detecting compressional waves of small intensity transmitted through water, which comprises a generally conical member mounted at its base end on a vibratory element or diaphragm and supporting at its reduced end a coaxial magnetostriiction tube.

Another object of the invention is to provide a microphone of the character described in which the magnetostriiction tube is disposed within an independently supported coil and contains a polarizing magnet, whereby compressional waves transmitted to the tube from the base of the conical member cause the generation of an electromotive force in the coil corresponding in magnitude to the intensity of the compressional waves.

A further object of the invention resides in the provision of a novel magnetostriuctive microphone for use in automatically directed antisubmarine torpedoes to detect compressional waves of small intensity from the submarine, which is of rugged construction and occupies a relatively small space in the torpedo.

These and other objects of the invention may be better understood by reference to the accompanying drawing, in which:

Fig. 1 is a side view, partly in section, of part of a torpedo employing one form of the new microphone;

Fig. 2 is an enlarged longitudinal sectional view of the head portion of the torpedo, showing one of the microphones illustrated in Fig. 1;

Fig. 3 is a detail view in section showing the connection between the magnetostriiction tube and the conical member illustrated in Fig. 2;

Fig. 4 is an exploded perspective view of part of the microphone shown in Fig. 2, and

Fig. 5 is a sectional view on the line 5—5 in Fig. 2.

The new microphone, as illustrated, is in a form suitable for detecting high-frequency compressional waves transmitted through water. While the microphone is adapted for various uses, it may be used to particular advantage in an electrically controlled azimuth steering system for torpedoes, as disclosed in a copending application of C. K. Stedman et al., Serial No. 502,075, filed September 11, 1943.

2

Referring to the drawing, the torpedo comprises a cylindrical hull 10 and a generally hemispherical head 11, which may be spun from sheet metal. The head is connected to the front end of the hull in any suitable manner, as by means of bolts 12 disposed in an annular recess in the head. A fuse 13 is mounted on the inner wall of the head and disposed axially therein, and on opposite sides of the fuze are two microphones, or "ears" 14 and 14a made in accordance with the invention. The microphones are disposed in a common horizontal plane with their axes converging toward the fuze axis at an angle of substantially 45 degrees, whereby each microphone is operable in an optimum direction to the exclusion of the other. The high explosive charge (not shown) may be packed around the fuze 13 and the microphones. Since the microphones 14 and 14a are identical in construction, a description of one of them will suffice.

The microphone comprises a solid member 16 of generally conical shape which is made of metal, such as brass. At its base, the conical member 16 is carefully fitted to the inner face of the hemispherical head 11, the cone being secured to the head in any suitable manner, as by means of a screw 17 threaded into the central portion of the cone. In fitting the base of the cone to the inner face of the head 11, one of the opposing surfaces may be coated with lampblack, or the like, and the surfaces pressed together to make an imprint of the uncoated surface. The surface not having the lampblack may then be scraped in accordance with the imprint to provide a closer fit. This fitting operation is desirable for the reason that the head 11 is not likely to have a perfectly true spherical form. After the fitting operation is completed, the base of the cone 16 and the opposing surface of the head 11 are preferably heated, coated thinly with soft solder and pressed tightly together, the screw 17 being in place but not completely tightened. The cone 16 is then oscillated slightly about its axis so as to eliminate any possible air bubbles in the solder and obtain as nearly as possible a perfect mechanical fit. Then the screw 17 is tightened and the parts are cooled slowly, so as to prevent the setting up of internal stresses.

It has been found by experience that the close fitting of the base of cone 16 to the opposing surface of the head 11 is an important factor. Compressional sound waves striking against the head 11 are almost entirely reflected from those parts of the head which are not solidly backed. The relatively massive cone 16, when connected to the

head with a good fit as described, affords a favorable acoustical impedance match, and the sound waves impinging upon the part of the head backed by the cone proceed in the direction of the axis of the cone and toward its apex or reduced end. The taper of the cone 16 apparently enhances the local intensity of the waves.

At its apex end, the cone is finished off with an external shoulder 18 against which one end of a nickel tube 19 is closely fitted, a reduced extension of the cone extending into and closely engaging the inner wall of the tube. The tube 19 may be held in position on the cone by a ring of soft solder 20 around the junction.

Surrounding the cone 16 and spaced therefrom is a housing comprising a frusto-conical shield 22 surmounted by a cylindrical shield 23, the two shields being joined in any suitable manner, as by means of a ring of solder 24. At its base, the shield 22 is connected to the inner face of the head 11 in concentric relation to cone 16, as by means of a weld 22a. The inner end of the shield 23 is closed by a cap 25 having a flange which fits closely around the shield. Near the juncture of the shield members 22 and 23 is an internal, shelf-like, annular ring 26 which fits closely in the shield 23 and is staked thereto, as shown at 27. A spool 28 made of insulating material is supported on the shelf 26 and has a winding or coil 29. The spool 28 fits loosely around the nickel tube 19 and is held in position against the shelf 26 by a spacer 30 under the cap 25. Lead wires 31 from the coil 29 extend outwardly through a recess 32 in the spacer and through an aligned slot 33 in the shield 23.

Within the nickel tube 19 is a permanent bar magnet 35, which may be made of "alnico" or other suitable material, the magnet being loosely supported in any convenient manner. As shown, one end of the magnet 35 is seated on the reduced end of cone 16, and the other end of the magnet terminates short of the outer end of tube 19. The field of the magnet 35 completes its circuit partly through the walls of the nickel tube 19, and, therefore, the magnetic attraction causes the magnet to cling to the inner face of the tube. It will be apparent that there is no direct mechanical contact connection between the tube 19 and the shield 23, or only a loose contact connection, except that both are supported by the head 11.

The congressional waves transmitted through the water against the part of head 11 adjacent cone 16 set up waves in the head, and these waves enter the cone and proceed along its axis toward its apex end. The waves continue into and along the nickel tube 19 and cause corresponding stresses of alternating compression and tension along the length of the tube. The high frequency of the waves and the inertia of the tube 19 are

such that a corresponding magnetostriction effect is produced in the tube. That is, the effect of these stresses is to generate a corresponding magnetic field in the tube 19, which is superimposed upon the steady field due to the magnet 35. To a great extent, the return path of the alternating flux is not through the magnet 35 but is through the air around coil 29. In other words, the alternating flux generated by the waves of compression and tension in the nickel tube 19 links with the coil 29 and generates a corresponding electromotive force therein. Thus, the energy of the waves transmitted through the water against the head 11 is received by the microphone and converted into electromotive forces in the coil 29.

It will be apparent that the new magnetostrictive microphone may be readily assembled and is of rugged construction. The shield 22-23 not only serves to support the coil 29 independently of the nickel tube 19 and the magnet 35, but also protects the cone 16 and the parts mounted thereon from the high explosive charge which is packed around the fuze 13 in the head.

We claim:

A directionally selective microphone for receiving compressional waves through a metallic wall, which comprises a generally conical member connected at its base to said wall, a frusto-conical shield secured at its base to said wall and surrounding said member, a magnetostriction tube connected to the reduced end portion of the conical member and disposed coaxially thereof, a cylindrical shield surmounting said frusto-conical shield and containing said tube, a coil extending around the tube and supported by said cylindrical shield independently of the tube and the conical member, and a polarizing magnet within the tube.
